UNITED STATES PATENT OFFICE.

JONATHAN MOORE, OF BROOKLYN, NEW YORK, ASSIGNOR TO HIMSELF
AND ABRAM HORTON, OF SAME PLACE.

DESIGN FOR BORDER FOR VASES, &c.

Specification forming part of Design No. 5,548, dated February 20, 1872.

I, JONATHAN MOORE, of Brooklyn, in the county of Kings, State of New York, have invented and produced a new and original Design for Borders for Vases and Fountains, of which the following is a specification:

I propose to designate my design by the words vine, leaf, and flower. Its nature is fully represented in the accompanying photographic illustration, to which reference is made, and in which—

A represents a large leaf of the *Acanthus* variety. B B represent smaller leaves, and C C a still smaller gradation of leaf. D D are stems of connecting vines, and E is a broadly-spread flower depending from the stem E'.

The design is intended to be executed in relief on cast-iron surfaces. It may form the border of a vase or other ornamental or useful casting; or it may form a zone, either alone or in connection with other ornaments, at a distance from the edge. Its principal intent, as before suggested, is to form a decoration at or near the edges of vases and fountains.

I claim as my invention—

The design for a decorative ornament on castings, as shown.

JONATHAN MOORE.
